Primary Examiner — Sandra S Snapp*Assistant Examiner* — Ieisha N Price(74) *Attorney, Agent, or Firm* — Crowe & Dunlevy, P.C.(57) **CLAIM**

The ornamental design for a stalk cutter device, as shown and described.

DESCRIPTION

FIG. 1 is a perspective view of a stalk cutter device showing the design in use in an open position.

FIG. 2 is a perspective view of the stalk cutter device shown in a closed position.

FIG. 3 is a side elevation view of the stalk cutter device, and the opposite side view is a mirror image thereof;

FIG. 4 is a top plan view of the stalk cutter device;

FIG. 5 is a bottom plan view of the stalk cutter device;

FIG. 6 is a front elevation view of the stalk cutter device; and,

FIG. 7 is a rear elevation view of the stalk cutter device. The ornamental design which is claimed is shown in solid lines in the drawings. The broken lines shown in the figures represent portions of the stalk cutter device that form no part of the claimed design. The broken line showing of the stalk in FIGS. 1 and 2 illustrates the environment of the claimed design and forms no part thereof. The claimed design is shown with a symbolic break in its length. The appearance of any portion of the article between the break lines forms no part of the claimed design.
